US00D629969S

(12) **United States Design Patent**
Wonderley

(10) **Patent No.:** US D629,969 S
(45) **Date of Patent:** ** Dec. 28, 2010

(54) **RAZOR CARTRIDGE PROTECTOR**

(75) Inventor: **Jeffrey W. Wonderley**, Fort Defiance, VA (US)

(73) Assignee: **American Safety Razor**, Verona, VA (US)

(**) Term: **14 Years**

(21) Appl. No.: **29/361,438**

(22) Filed: **May 11, 2010**

(51) **LOC (9) Cl.** **28-03**

(52) **U.S. Cl.** **D28/47**

(58) **Field of Classification Search** 30/32, 30/34.05, 34.1-34.2, 41, 44-46, 47-51, 57-58, 30/77-84, 526-536, 537-539; D28/44-49

See application file for complete search history.
